EAR-WIRE

Frank Hodge Davidson, Los Angeles, Calif.

Application August 16, 1954, Serial No. 31,888

Term of patent 14 years

(Cl. D45—9)

FIG. 1.

FIG. 2.

FIG. 3.

FIG. 4.

To all whom it may concern:

Be it known that I, Frank Hodge Davidson, a resident of Los Angeles, California, have invented a new, original, and ornamental Design for an Ear-Wire, of which the following is a specification, reference being had to the accompanying drawing, forming a part hereof.

Fig. 1 is a front elevational view of an ear-wire showing my new design;

Fig. 2 is a side elevational view thereof;

Fig. 3 is an end elevational view thereof; and

Fig. 4 is a cross-sectional view thereof taken along the line 4—4 of Fig. 1.

I claim:

The ornamental design for an ear-wire, as shown.
